UNITED STATES PATENT OFFICE

2,581,815

EXPLOSIVE RIVET GUN TIP ASSEMBLY

Paul B. Rakowski, Jr., Baltimore, Md., assignor to
The Glenn L. Martin Company, Middle River,
Md., a corporation of Maryland

Application March 9, 1949, Serial No. 80,491

1 Claim. (Cl. 218—19)

1

This invention relates generally to the art of working explosive rivets and, more particularly, to an improved explosive rivet gun tip assembly.

The use of explosive rivets having a hollow shank spaced inwardly of a head portion and filled with a heat sensitive explosive, adapted to be exploded on application of a predetermined amount of heat to the head, has become a common practice. Furthermore, in order to attain high speed production it is highly desirable that the time required to explode such a rivet be as short as possible. However, one of the problems of working explosive rivets is to avoid premature explosion of the rivet charge before the rivet is properly seated. This occurs if for any reason the rivet does not properly seat as it is being heated. Thusly, the normal exploding time of the rivet is consumed in the attempt of the worker to position the rivet by means of the heated gun. With the conventional type of rivet exploding gun or iron, the explosive rivet is seated and exploded by having the hot tip of the gun pressed thereagainst as one operation. Once the heating of the rivet is started, even though the rivet fails to align properly in the rivet hole, the operator has no alternative other than to hold the rivet gun in contact with the rivet until it explodes so as to avoid the risk of having the rivet explode in his face upon removal of the gun. A rivet so exploded, not only constitutes a defective rivet that must be replaced, but, also, may result in damage to the sheet material being riveted. In either case, the cost of replacement or repair is not only costly in time but seriously delays the working schedule of such an operation.

My invention provides a solution to these problems by providing an improved explosive rivet gun tip assembly having a movable ring mounted forwardly of the heated end of a rivet gun as a guard against premature contact of said heated portion with a rivet head centered therein and adapted to allow forward movement of the heated rivet gun end into engagement with the center of the rivet head to explode it on application of additional predetermined force to the gun.

It is one of the objects of this invention to provide an apparatus for controlling exploding of explosive rivets so as to avoid the dangers and disadvantages of the conventional type of rivet exploding gun, having an unguarded hot tip.

Another object is to provide an explosive riveting device wherein a rivet engaging pressure pad is spaced forwardly of a rivet heating mem-

2

pad to effect engagement with the rivet on the application of force applied axially of the rivet gun.

Still another object is to provide explosive rivet detonating means wherein the detonating member is sheathed within a rivet engaging ring.

A still further object is to prevent premature or accidental explosion of explosive rivet by sequentially engaging and holding said rivet and applying heat thereto.

Another object is to provide a riveting gun having a wear-resistant rivet head engaging means mounted forwardly of a rivet engaging tip.

Other objects of this invention will become apparent from the following description when taken in conjunction with the accompanying drawing, in which like numbers refer to like parts in different views.

In the drawing:

Fig. 1 is a sectional view of the present invention installed on a conventional type of hot rivet gun fragmentarily shown.

Fig. 2 is a sectional view of the device showing the pressure ring in encircled engagement with a rivet head and the rivet exploding portion of the rivet gun in aligned engagement with said rivet.

Fig. 3 is an end view of the device taken on line 3—3 of Fig. 1.

Referring more particularly to Fig. 1, the device of this invention is comprised of a housing 10 adapted for sleeve-like mounting over the end of a conventional type of hot rivet gun 11 having an iron portion 12 arranged as a rivet heating iron adapted for movement within the housing to engage a rivet head and conduct heat thereto. The rivet heating iron 12 is generally that of a conventional type of rivet exploding gun and is preferably made of copper or an alloy metal characterized by its high heat conductivity. Rearwardly of the iron 12 is a barrel portion 13 having an increased cross-section with a shoulder 26 formed adjacent the iron. Both the iron 12 and the barrel portion 13 are adapted for insertion in the gun 11 in a conventional manner such as by threaded engagement therewith. The iron 12 is heated by a conventional type of heating unit 28 placed interiorly of the gun 11 with one end of the heater being extended within the iron for conduction of heat thereto. The heating unit 28 is energized from a suitable electrical supply circuit (not shown).

In the extreme forward end of hot iron portion 12 is a concaved point 17 adapted for matched engagement with the rounded head of

an explosive rivet. The housing 10 is formed generally cylindrical of a suitable lightweight metal such as aluminum so as to add as little additional weight to the gun assembly as possible. The inner dimensions of the housing 10 are arranged to provide a slide fit over the hot iron portion 12 and the barrel 13 with the concaved point portion of the iron centered thereto. Limited axial movement of the housing 10 relative to the gun 11 is provided by a longitudinally extending closed-ended slot 16 formed in the outer surface of the barrel 13 of the gun into which the end 25 of a set screw 15, carried by the housing 10, protrudes.

Positioned around the iron 12 is a spring 14 placed in compression between a shoulder 26, formed inwardly and normal to the barrel 13, and an abutment 27 formed internally of the housing 10. In this manner, the urge of spring 14 having one end positioned against the shoulder 26 of the gun and the other end positioned against the abutment 27 carried by the housing, tends to urge the housing forwardly to sheath the hot iron 12 to the extent provided by the closed slot 16 into which the set screw 15 protrudes. Forward movement of the iron relative to the housing is readily accomplished by the exertion of sufficient pressure against the gun 11 with the housing held against forward movement to overcome the urge of spring 14.

The outer end of the housing 10 is formed with a threaded portion 18 adapted to receive a circular insert 19 proportioned to overhangingly engage the outer periphery of a rivet head to be riveted. This is best illustrated in Fig. 2 which shows the insert 19, having its inner diameter smaller than the outside diameter of the rivet head, positioned in peripheral engagement with the head of an explosive rivet 20, having a shank portion 21 inserted through metal sheets 22 and 23 for riveting. This arrangement of the insert 19 is used to properly seat the rivet 20 with the head in engagement with the outer surface of the sheet 22 as the gun iron 12 is forced forwardly against the compression spring 14. The inner periphery of the insert 19 is slightly greater than the outer periphery of the end of iron 12 to provide for free movement of the point 17 into engagement with a rivet head centered within the insert. The sheathing effect of the hot end 12 of the rivet gun not only guards against accidental heating of a particular rivet but also the adjacent rivets of a rivet assemblage. Undue wear of the point 17 is also avoided as contact between it and the rivet being worked is limited to an aligned pressure engagement.

The insert 19 is preferably formed of wear-resistant hard metal as compared with the soft metal of the heating iron which provides for long services without an appreciable change in dimensions so as to effect the heat transfer characteristics of the gun. The insert, being removable, also provides for a plurality of tip sizes necessary in the working of different sized rivets.

Figure 3 shows the cooperative relationship of the concaved point 17 relative to the insert 19 adapted for centering over a rivet head to be riveted. The point 17 is so centered with relation to the insert 19 that uniform engagement of the rivet head is assured which tends to produce a more uniform riveting operation.

The operation of my device when installed in combination with a suitable rivet gun is that the hot iron portion 12 is drawn within the housing

10 by the urge of spring 14. In this position the iron 12 is heated sufficiently to explode rivet 20 inserted in sheets 22 and 23 to be riveted. The next step is to center the housing end or insert 19 over the head of rivet 20. With the insert in engagement with the rivet head, sufficient additional pressure is applied to the gun 11 to fully seat the rivet and move the hot iron point 17 forwardly into engagement with the center of the rivet head. In this position the rivet head is fully surrounded by the housing and the rivet explosion starting time is accurately controlled as there can be no accidental heating of the rivet.

Although my invention has been shown and described in considerable detail, it will be appreciated that certain changes, alterations, modifications, and substitutions can be made without departing from the spirit and scope of the claim.

I claim as my invention:

20 A tool for heating the head end of explosive rivets comprising a rivet heating gun having a main body portion, a tip member of high heat conductivity rigidly carried by said body portion and extending axially forwardly therefrom, said tip member having a forward portion of one diameter and a rear portion of a larger diameter providing an external circumferential shoulder, and heating means carried within the said body for heating said tip member to a relatively high 30 temperature, a sleeve-like housing slidably carried directly on said tip member for only limited axial movement relative thereto, said housing including an internal circumferential shoulder in axial alignment with the shoulder of the tip member, and a seating ring of wear-resistant 35 material secured to said housing and extending forwardly thereof and being provided with an opening extending axially therethrough whereby to provide a pressure surface surrounding said 40 opening adapted for applying force axially forwardly directed, and spring means positioned between said shoulders normally urging said housing forwardly relative to said tip member, means for stopping such forward movement of the housing at a position wherein said tip member is 45 spaced axially inwardly from said pressure surface, said gun being movable forwardly against the reaction of said spring means when said seating surface is held against forward movement 50 whereby the forward end of said tip member will be moved into close proximity to said seating surface and into position to contact the head of such a rivet extending rearwardly into said opening for applying heat thereto.
